US0D1071715S

(12) **United States Design Patent** (10) **Patent No.:** **US D1,071,715 S**
(45) **Date of Patent:** **** Apr. 22, 2025**

(54) **ADJUSTMENT SHAFT**

(71) Applicant: **ASM IP Holding B.V.**, Almere (NL)
(72) Inventor: **George B. Jackson**, Phoenix, AZ (US)
(73) Assignee: **ASM IP Holding B.V.**, Almere (NL)
(**) Term: **15 Years**
(21) Appl. No.: **29/856,099**
(22) Filed: **Oct. 11, 2022**
(51) LOC (15) Cl. **08-08**
(52) U.S. Cl. **D8/382**
USPC **D8/382**
(58) **Field of Classification Search**
USPC **D8/382**
CPC F16D 3/38; F16D 3/40; F16C 11/00; F16C 11/06
See application file for complete search history.

Primary Examiner — Rachel A. Voorhies

Assistant Examiner — Benjamin D. Wannemacher

(74) *Attorney, Agent, or Firm* — Snell & Wilmer L.L.P.

(57) **CLAIM**

The ornamental design for an adjustment shaft as shown and described.

DESCRIPTION

FIG. 1 is a front perspective view of the adjustment shaft, showing my new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing of the adjustment shaft are for the purpose of illustrating portions of the article and form no part of the claimed design.

1 Claim, 7 Drawing Sheets
